UNITED STATES PATENT OFFICE.

WILLIAM LAWRENCE, OF WORCESTER, MASSACHUSETTS.

FLANGEWAY-RAIL FOR RAILROAD CROSSINGS AND BRIDGES.

SPECIFICATION forming part of Letters Patent No. 399,149, dated March 5, 1889.

Application filed October 15, 1888. Serial No. 288,112. (No model.)

To all whom it may concern:

Be it known that I, WILLIAM LAWRENCE, a citizen of the United States, residing at Worcester, in the county of Worcester and State of Massachusetts, have invented certain new and useful Improvements in Flangeway-Rails for Railroad Crossings and Bridges, of which the following, together with the accompanying drawings, is a specification sufficiently full, clear, and exact to enable persons skilled in the art to which this invention appertains to make and use the same.

The objects of my present invention are to provide a rolled metal rail of peculiar construction and adapted to be used in the flangeway of railroad crossings and bridges to protect the planking, prevent horses' feet from becoming caught by their shoe-calks in the groove, and to form a substantial guard and channel for the car-wheel flanges that can be easily kept free from accumulation of dirt, snow, or ice. These objects I attain by a rail constructed as herein shown, and adapted to fit against the railroad-rail in the peculiar manner described.

In the drawings, Figure 1 is a plan view of a railroad-crossing, illustrating my invention as applied to use. Fig. 2 is a view of my improved flangeway-rail; and Fig. 3 is a sectional view showing the car-track rail, flangeway-rail, and crossing-planks in their relative arrangement as when laid for use.

In the drawings, A denotes my improved flangeway-rail, B indicates the car-track rail, and C the crossing-planking.

My flangeway-rail is made as an improved merchantable product or manufacture of rolled iron or steel, in bars of convenient length for use, and is of the peculiar shape or section shown. The bottom surface, d, is flat or of a form that will give a bearing at the front and rear parts thereof. The forward lower part extends outward in a flange, e, for abutment against the side of the track-rail web b, while above said flange the metal is carried up in a lip, f, having a vertical front and an inclined top surface that fits against the lower angle, h, of the track-rail head.

The rear side of the rail c is made straight and substantially vertical to match against and support the planks C, the metal being formed into a narrow lip, m, that extends to

a height that will be substantially level with the lap of the track-rail, and which lip is for the purpose of a flange-guard and to protect 55 the top corner of the planking C from abrasion and wear.

Between the lips f and m the top of the rail is formed with a cavetto or semicircular channel, F, of a depth which, when the rail 60 is placed in conjunction with the head of the track-rail, forms a flangeway some one-half inch (more or less) greater than the depth of the car-wheel flanges and some two inches (more or less) in lateral width. The contour 65 of the curved surface of said channel F is such as to coincide with or continue the inside surface of the rail-head substantially without interruption at the junction of the lip f and rail-head at h, my rail thus forming, when in combination with the track-rail, a clean smooth trough or flangeway, from which substances would naturally be crowded by the action of the wheel-flanges running 70 therethrough, such substances being forced 75 up and over the inclined inner surface of the lip m. It also forms a flangeway that can be easily and conveniently cleared from snow, ice, or other accumulation, and one which forms a safeguard against injury to horses by 80 reason of their feet becoming caught by the shoe-calks locking between the planking and track, or under the rail-head, as frequently occurs with ordinary crossings.

The flangeway-rail is held in place by the 85 lip f, held to the rail-head by the planking resting against the back of the rail; or, if preferred, spikes may be driven through holes formed in the bottom of the channel. The rail, when in use, is supported by suitable 90 blocks or chairs, s, placed on the ties G.

If it is desired to make the flangeway-rail with less weight of metal, it can be rolled with a groove in the straight bottom or side, as indicated by dotted line in Fig. 3. 95

I am aware that various forms of guards for the flangeways of railway-crossings have heretofore been described and patented. It will therefore be understood that I do not claim, broadly, the combination, with a track 100 and crossing, of a guard for such purpose irrespective of its construction; but my invention is the guard-rail of peculiar and improved shape, as described.

What I claim as of my invention, and desire to secure by Letters Patent, is—

1. As an improved article of manufacture, the within-described rolled metal rail shaped as shown, with the lateral flange *e* at its forward lower part, the lip *f* at the upper front corner, the upright rear edge, *c*, and upwardly-extended guard-lip *m*, and the channel *F*, having the hollow rounded contour between the said lips, all as shown and described.
2. The combination, with the track-rail *B* and crossing-plank *C*, of the rolled flange-way-rail *A*, having the lateral projecting flange *e* at its forward lower part abutting

against the web of the track-rail, the upwardly-directed lip *f*, matching against the lower corner of the track-rail head, the upright back *c*, and guard-lip *m*, sustaining the crossing-plank, and the rounded channel *F* between said lips *f* and *m*, all as shown and described. 15 20

Witness my hand this 11th day of October, A. D. 1888.

WILLIAM LAWRENCE.
